(57) **CLAIM**

The ornamental design for a hand-held container, as shown and described.

DESCRIPTION

FIG. 1 is a perspective view of the hand-held container, as viewed from the top, rear, and right side;

FIG. 2 is a top plan view of the hand-held container of FIG. 1;

FIG. 3 is a front elevational view of the hand-held container of FIG. 1; and,

FIG. 4 is a bottom plan view of the hand-held container of FIG. 1.

Right and left side elevation views have been omitted because the claimed portion of the design is not visible from these views.

The broken lines in the drawings represent unclaimed portions of the handheld container and form no part thereof. Additionally, contour lines are also unclaimed, and are shown in broken lines to give an understanding of the shape of the unclaimed surface on which the claimed elements sit.

UNITED STATES PATENT AND TRADEMARK OFFICE
Certificate

Patent No. D. 627,119 S

Patented: November 9, 2010

On petition requesting issuance of a certificate for correction of inventorship pursuant to 35 U.S.C. 256, it has been found that the above identified patent, through error and without any deceptive intent, improperly sets forth the inventorship.

Accordingly, it is hereby certified that the correct inventorship of this patent is: Mark W. Bergman, Minnetonka, MN (US); Matthew V. Leyden, St. Paul, MN (US); and Jeffrey B. Waffensmith, North Oaks, MN (US).

Signed and Sealed this Second Day of July 2013.
